UNITED STATES PATENT OFFICE.

CHRISTIAN CLAUDY, OF BIRMINGHAM, ALABAMA.

DESIGN FOR A MONUMENT.

SPECIFICATION forming part of Design No. 23,365, dated June 12, 1894.

Application filed May 7, 1894. Serial No. 510,407. Term of patent 7 years.

To all whom it may concern:

Be it known that I, CHRISTIAN CLAUDY, a citizen of the United States, residing at Birmingham, in the county of Jefferson and State of Alabama, have invented and produced a new and original Design for a Monument; and I do hereby declare the following to be a full, clear, and exact description of the same, reference being had to the accompanying drawing, forming a part thereof.

The figure is a vertical front view showing my design for a monument for graves.

The leading feature of my design consists of a base having a slab, the slab having a raised rim surrounding the slab on the outer edge, a series of panels with raised rim on their edges placed in the center of the slab, the spaces between the center panels and outer rim being filled with panels of flowers and scroll work.

A is the base slightly tapering on the sides toward the top, a chamfer B surrounding the upper edge. Extending upward from the base is a slab C formed with a concave molding D at the bottom adjoining the base, a raised rim K extending from the concave

molding surrounding the slab at the outer edges, a raised bead E extending across the slab between the rims. An emblem panel F to attach emblems of various kinds, or to enamel them on the panel, is placed in the center between the rims, the panel is provided with scroll work in the corners as shown. A name panel G is placed above the panel F. Above the panel G between it and the top rim, is placed a panel H, this panel is also intended for emblems, all the center panels are surrounded, separated and connected by a slightly raised rim I. The space between the panels, and between the panels and outer rim 40 of the slab, is filled in with a panel J composed of vines with flowers, and scroll work substantially as represented.

What I claim is—

The design for a monument herein shown 45 and described.

In testimony whereof I affix my signature in presence of two witnesses.

CHRISTIAN CLAUDY.
